Term of patent 14 years

Int. Cl. D7—03

U.S. Cl. D7—137

FIG. 1 is a front elevational view of an article of flatware showing my new design as embodied in a fork;

FIG. 2 is a cross-sectional view taken on the line 2—2 of FIG. 1;

FIG. 3 is a cross-sectional view taken on the line 3—3 of FIG. 1;

FIG. 4 is a cross-sectional view taken on the line 4—4 of FIG. 1;

FIG. 5 is a cross-sectional view taken on the line 5—5 of FIG. 1;

FIG. 6 is a cross-sectional view taken on the line 6—6 of FIG. 1;

FIG. 7 is a side elevational view from the right of FIG. 1, the side opposite being a mirror image thereof;

FIG. 8 is a rear elevational view thereof; and,

FIG. 9 is a perspective view of an article of flatware showing my new design as embodied in a spoon.

The distinguishing feature of my new design for an article of flatware resides in the handle configuration.

I claim:

The ornamental design for an article of flatware, as shown and described.
